(57) **CLAIM**

The ornamental design for a signal transfer connector, as shown and described.

DESCRIPTION

FIG. 1 front, top, right side perspective view of a signal transfer connector, showing our new design;

FIG. 2 is a front, bottom, right side perspective view thereof;

FIG. 3 front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the signal transfer connector that form no part of the claimed design.

1 Claim, 7 Drawing Sheets
